J. G. DOTY

VISIBLE DISPENSING DEVICE

Filed July 28, 1924

Inventor,
Gerald G. Doty,
by his attorney, Frankland.
His Attorneys.

UNITED STATES PATENT OFFICE.

JERALD G. DOTY, OF ST. LOUIS, MISSOURI.

VISIBLE DISPENSING DEVICE.

Application filed July 28, 1924. Serial No. 728,632.

To all whom it may concern:

Be it known that I, JERALD G. DOTY, a citizen of the United States, residing at the city of St. Louis and State of Missouri, have invented a new and useful Visible Dispensing Device, of which the following is a specification.

This invention relates to visible dispensing devices.

10 The invention is specially designed and adapted for use as a visible dispensing device for gasoline at filling stations, etc., though the usefulness of the invention is not limited as it may be advantageously applied 15 to other uses.

An object of the invention is to provide an improved visible dispensing device including a receptacle connected with a supply line through which gasoline or the like is admitted to the receptacle, and provided 20 with a quick closing valve within the receptacle and operated by a float device controlled by the gasoline when the gasoline reaches a predetermined height in the receptacle.

Another object of the invention is to provide a device embodying the subject matter mentioned in which the valve opens automatically and as an incident to the withdrawal of the gasoline from the receptacle.

Other objects will appear from the following description, reference being made to the drawing in which—

35 Fig. 1 is a vertical sectional view of my improved visible dispensing device.

Fig. 2 is a cross sectional view on the line 2—2 of Fig. 1.

Fig. 3 is a relatively enlarged sectional view showing the construction and arrangement of the valve which is controlled by the float to close the supply line.

Fig. 4 is a detailed view of the adjustable device limiting movement of the valve operating lever.

45 Fig. 5 is a view showing the connection of a part of the valve operating lever with the valve stem.

Fig. 6 is an enlarged sectional view showing the pivotal connection of the float with one of the valve operating levers.

The receptacle comprises a transparent glass tube 1, an upper end wall 2, a lower end wall 3 and a tie rod in the form of a tube 4 extending axially through the tube 1 and securing the end walls against the ends of said tube. The lower end wall 3 has an out-

let opening 5 for connection with a delivery hose that conducts the gasoline to the point of delivery. The upper end wall 2 has a vent 6 through which the air passes from the 60 receptacle as the gasoline enters.

The supply line for delivering gasoline or other liquid into the receptacle comprises a pipe 7 extending upwardly through the lower end wall 3 and having its upper end 65 terminating some distance below the top of the receptacle. To the upper end of the pipe 7 a tubular fitting 8 is attached, the same being provided with a cross web 9. A valve seat member 10 is secured to the fitting 8 70 and has a valve seat 11 around the discharge opening thereof. The tube 12 encloses the pipe 7 and forms an annular space around said pipe opening near the bottom of the receptacle. The upper end of the tube 12 comprises an enlarged portion 13 to receive the valve mechanism including the parts 8 and 10. An end wall 14 is secured within the upper end of the enlarged portion 13 at a distance from the end of the valve seat member 10 so that the gasoline or other fluid entering the receptacle from the pipe 7 may pass between said parts and through the tube 12 to fill the receptacle to the proper height. 75

80 A valve stem 15 extends for sliding movements through holes in the cross web 9 and the end wall 14 and has an elastic valve 16 attached thereto within the valve seat member 10 and above the fitting 8. The stem 15 has a hole 17 through which a lever member 18 extends. The lever member 18 is pivoted to a support 19 on the end wall 14 and on its upper edge has a rounded shoulder 20 within the hole 17. The shoulder 20 operates against a roller 21 supported above the lever member 18 and in the hole 17 by a pin 22. A lever 23 has one end pivoted to the support 19. The free end of the lever member 18 supports a pin 24 and a similar pin 25 is supported by the lever 23. The pins 24 and 25 are connected by coil springs 26, the power of which is exerted to raise or to lower the ends of said levers 18 and 23 when said levers pass dead center in either direction. A block 27 is pivoted to the free 100 end of the lever 23. A float 28 has a stem 29 extending through and connected with the block 27. A coil spring 30 encircles the rod 29 and has one end bearing against the block 27 and the other end against the float 28. 110 A stem 31 from the lower end of the float 28 extends through a guide 32 attached to

the tubular rod 4 and may be equipped with a weight 33 on its lower end, as shown.

Extent of movement of the lever 23 is limited by an abutment device comprising 5 an arm 34 adjustably secured to the part 13 by screws 35 passing through a slot 36 in said arm. The arm 34 is formed with a notch 37 in which the lever 23 operates, the upper and lower ends of said notch constituting abutments to limit extent of movement of said lever.

A lubricating device 38 may be provided in connection with the upper end wall 2 of the receptacle to conduct lubricant to the 15 pivot of the levers 18 and 23. A portion of the lubricant will naturally pass along the lever 18 to the connection of said lever with the stem 15. Flow of liquid through the supply line into the receptacle is expedited 20 by provision of a vent 39 in the wall 14.

When gasoline or other liquid is admitted into the receptacle 1 the float 28 will be raised thereby until the lever 23 passes dead center position with respect to 25 the lever 18. When this occurs the springs 26 will raise the free end of the lever 18, thereby moving the valve 16 to closed position against the valve seat 11 and stopping flow of gasoline or other liquid into the receptacle. This operation occurs quickly and at the moment the liquid reaches the predetermined height in the receptacle. When the valve is closed operation of the pump, forcing the liquid through the supply line 7, is 30 necessarily stopped so that when the liquid is withdrawn from the receptacle 1 the weight of the float 28 and connecting parts will actuate the lever 23 downwardly beyond dead center position with respect to the lever 18, whereupon the springs 26 act quickly to open the valve 16. The pump may be then again operated to fill the receptacle. The operation of the valve to open and closed positions occurs quickly and automatically and as an incident to the other operations described.

The construction, arrangement and relationship of the parts may be varied within equivalent limits without departure from 50 the nature and principle of the invention.

What I claim is:—

1. A visible dispensing device comprising a receptacle, a pipe opening into the receptacle, a tube enclosing the discharge end of 55 said pipe within the receptacle, a tubular fitting attached to said pipe within said tube, a valve chamber in connection with said fitting having an outlet therethrough to said tube, a valve enclosed in said chamber, a stem extending from said valve through said outlet and through the end of 60 said tube, a lever pivotally supported by said tube engaging said stem, a second lever pivotally supported by said tube and movable vertically to positions beyond dead cen-

ter on opposite sides of its pivot with respect to said first named lever, a spring connecting said levers on opposite sides of their pivots, and a float connected to the outer end of said second lever.

2. A visible dispensing device comprising a receptacle, a pipe opening into the receptacle, a tube enclosing the discharge end of said pipe within the receptacle, a valve chamber in connection with said pipe having an opening therethrough to said tube, a valve within said chamber movable to open position in a direction toward the end of said pipe and to closed position in a direction away from the end of said pipe, a stem in connection with the valve extending through said opening and through the end of said tube, a pair of levers having their adjacent ends pivoted upon said tube, a connection between one of said levers and said stem, a float in connection with the outer end of the other lever, and a spring connecting said levers on opposite sides of their pivot.

3. A visible dispensing device comprising 90 a receptacle, a pipe for conducting liquid into the receptacle, a tube enclosing the discharge end of said pipe within the receptacle, a valve chamber supported by said pipe within said tube and having an opening beyond the end of said pipe for admitting liquid into said tube, a valve in said chamber movable to open position toward the end of said pipe and to closed position in a direction away from the end of said pipe, a stem from said valve extending through said opening and through the end of said tube, a pair of levers having their adjacent ends pivoted upon said tube, a connection between one of said levers and 95 said valve stem, a spring connecting said two levers on opposite sides of their pivot, a float within said chamber, and a sliding connection between said float and the outer end of one of said levers.

4. A visible dispensing device comprising a receptacle, a pipe for conducting liquid into the receptacle, a tube enclosing the discharge end of said pipe within the receptacle, a valve chamber supported by said pipe within said tube and having an opening beyond the end of said pipe for admitting liquid into said tube, a valve in said chamber movable to open position toward the end of said pipe and to closed position 100 in a direction away from the end of said pipe, a stem for said valve extending through said opening and through the end of said tube, a pair of levers having their adjacent ends pivoted upon said tube, a connection between one of said levers and 105 said valve stem, a spring connecting said two levers on opposite sides of their pivot, a float within said chamber, a sliding connection between said float and the outer end of one of said levers.

of one of said levers, a spring between said float and the lever to which it is connected, and a guiding device for said float.

5. A visible dispensing device comprising
5 a receptacle, a pipe for conducting liquid
into the receptacle, a tube enclosing the dis-
charge end of said pipe within the recep-
tacle, a valve chamber within said tube re-
ceiving liquid from said pipe and having an
10 opening into said tube, a valve in said valve

chamber for opening and closing said opening, a stem extending from said valve through the end of said tube, a pair of levers pivoted to said tube, means for actuating one of said levers by the other, means 15 for operating said stem by the lever actuated as aforesaid, and means for operating said lever which actuates the other.

JERALD G. DOTY.
